US00D757516S

(12) **United States Design Patent**
Nesbitt

(10) **Patent No.:** **US D757,516 S**
(45) **Date of Patent:** **** May 31, 2016**

(54) **BRAKE BIAS ADJUSTER KNOB**

(71) Applicant: **Innovatech, LLC**, Chicago, IL (US)

(72) Inventor: **Bruce Nesbitt**, Chicago, IL (US)

(73) Assignee: **Innovatech, LLC**, Chicago, IL (US)

(**) Term: **14 Years**

(21) Appl. No.: **29/510,131**

(22) Filed: **Nov. 25, 2014**

(51) **LOC (10) Cl.** **08-06**

(52) **U.S. Cl.**

USPC **D8/307**

(57) **CLAIM**

The ornamental design for a brake bias adjuster knob, as shown and described.

DESCRIPTION

FIG. 1 is a top perspective view of a brake bias adjuster knob showing my new design.

FIG. 2 is a bottom perspective view of the brake bias adjuster knob of FIG. 1.

FIG. 3 is a front view of the brake bias adjuster knob of FIG. 1, the rear view being a mirror image thereof.

FIG. 4 is a left side view of the brake bias adjuster knob of FIG. 1, the right side view being a mirror image thereof.

FIG. 5 is a top view of the brake bias adjuster knob of FIG. 1; and,

FIG. 6 is a bottom view of the brake bias adjuster knob of FIG. 1.

The broken lines shown represent unclaimed subject matter and form no part of the claimed design.

1 Claim, 6 Drawing Sheets
